By W. A. Redmond, Atty.

UNITED STATES PATENT OFFICE.

JOHN WOOD, JR., OF CONSHOHOCKEN, PENNSYLVANIA.

WATER-TUBE BOILER.

SPECIFICATION forming part of Letters Patent No. 408,060, dated July 30, 1889.

Application filed March 12, 1889. Serial No. 302,981. (No model.)

To all whom it may concern:

Be it known that I, JOHN WOOD, Jr., a citizen of the United States, residing at Conshohocken, in the county of Montgomery and State of Pennsylvania, have invented certain new and useful Improvements in Water-Tube Boilers; and I do hereby declare the following to be a full, clear, and exact description of the invention, such as will enable others skilled in the art to which it appertains to make and use the same.

This invention relates to that class of steam-boilers known as "water-tube" boilers—that is, boilers in which the water circulates through the tubes instead of the products of combustion; and it has for its object to provide a boiler of this class in which the interior and exterior of the steam-drum, the end cylinders, and the tubes forming the boiler proper may be readily and easily accessible for the purpose of cleaning or repairing the same; and it consists of a steam-drum located above the tubes and connected by cylindrical necks with the cylinder-heads at each end of the boiler, said heads being constructed as hereinafter described, and provided with openings adapted to be closed by man-hole plates or covers, as is also the drum, and in other details of construction, as hereinafter described and claimed.

In the accompanying drawings, forming a part of this specification, Figure 1 is a side elevation, partly in section, and having one of the inclosing-walls broken away, of my improved boiler; Fig. 2, an enlarged vertical section through one of the cylinders; and Fig. 3, a detail view of the tube-sheet.

Similar letters refer to similar parts throughout the several views.

A represents the tube-cylinders, which are made up of the bodies or shells *a*, and the convex heads *b* and tube-sheets *c*, the bodies being riveted to the flanges *a'* of the convex heads and the flanges *c'* of the tube-sheets, as clearly shown in the drawings. The cylinders thus formed are of a size sufficiently large to admit a man within them through man-holes *d*, formed in the convex heads, for the purpose of repairing or cleaning the tubes when necessary.

The man-holes *d* are covered by plates *e*, in each of which a recess is formed to receive

the head of a screw-bolt *e'*, the outer end of which passes through an opening in a cross-bar or bridge *f*, which is cast integral with a ring of metal *f'*, forming the seat for the plate *e*, and receives a nut *g*, whereby the plate *e* may be drawn in place and securely held. In the tube-sheets *c* are drilled or otherwise formed holes *g'*, which are arranged in staggered series—that is, each series of holes breaks joint with the contiguous series. In these holes the tubes *B* are inserted and expanded and their ends flared or beaded, so that they will retain their set position without rivets or other fastenings.

The boiler, made up as described, is supported by means of brackets *h*, riveted to the sides of the cylinders which rest on the setting of the brick-work *C*, as shown. In the upper sides of the cylinders are formed circular openings *h'*, from which project necks *D*, the flanges of which are doubly riveted to the barrels of the cylinders around the edges of the openings. These necks form the connection between the cylinders and the steam-drum *E*, said drum being made up of any desired number of plates in a circular form and having its ends formed of convex heads *E'*, in one of which—preferably the front end—a man-hole is formed and provided with a plate *F*, cross-bar *F'*, and bolt *G*, in all respects similar to those described in connection with the cylinders, through which access may be readily had to the interior of the drum. The flanges of necks *D* are double-riveted to the under surface of the drum, at each end thereof, about the openings formed therein, so that the circulation between the boiler and steam-drum will be constant and perfect. The steam-drum is suitably supported on the brick-setting, and owing to the brackets *h* on cylinders *A*, forming the supports for the latter, all tensile strain is taken off of the necks *G*.

While I have described and shown one means for supporting the boiler, I do not wish to be restricted thereto, as it is evident the brick-work could be dispensed with and the boiler suspended from the top by means of side columns and girders or saddles to yokes riveted to the top of steam-drum directly under the saddles; or it may be set or hung in any other desirable or convenient manner.

In order to prevent the possibility of the cylinders from being blown off the tubes, I pass long stay-rods *H* through some of the tubes—say four, arranged at equal distance 5 from the centers of the tube-sheets—the ends of said rods being formed with solid crow-feet *m*, through which they may be securely riveted to the inner sides of the convex heads on each cylinder. The tubes *B*, owing to the 10 manner in which they are secured in the tube-sheets, also act as stays or braces to prevent the cylinders being blown off, thus forming a very strong and simply-constructed boiler, the cylinders of which are practically proof 15 against being blown off their tubes.

The boiler and steam-drum are so set that their ends are exposed, the latter being, in the construction shown, of greater length than the boiler and projecting beyond the setting, thus 20 giving ample storage-room for water and steam, while the boiler ends are protected by movable covers or doors *n*, making said ends readily accessible when it is desired.

The boiler is set at an angle or on a slight 25 incline, while the steam-drum is placed horizontal in the drawings, although they both may be horizontally arranged, if so desired.

K represents the front of the boiler-setting, which may be of iron, and is provided with the 30 fire-door *J* and ash and draft openings *L*.

M represents the grate in the fire-chamber.

O is the smoke-flue to the chimney and opens from the rear wall of the setting between the steam-drum and boiler proper in 35 the rear of neck *G* on rear end, and is provided with a damper *N*. The steam-pipe from the boiler, and other usual parts, are not necessary to be described, as I make no claim thereto.

40 Owing to the peculiar arrangement and construction of my boiler, the circulation is perfect. The tubes being of comparatively small diameter and subject or exposed to the full force of the products of combustion, the 45 water contained therein is rapidly converted into steam and a constant circulation maintained. The parts being subject to about the same heat throughout, there is no unequal expansion, and as there are no joints exposed 50 there will be no strain on them.

All that is required to be done when cleaning is actually necessary is simply to remove the man-hole plates at each end and ample access may be at once had to all the tubes. 55 In other boilers of this type with which I am familiar a great number of small caps or plugs have to be removed in order to gain access to the tubes, thus causing much annoyance, as well as expense and loss of time, while it is 60 often found impossible to remove these caps or plugs.

The fire-chamber, as shown, is so constructed that the gases will ascend at an angle to the tubes and other parts of the boiler, and, 65 passing up and down several times between

the staggered tubes and around the cylinders and lower surface of steam-drum, are thus brought in contact with all the heating-surface. The flame being broken or caused to travel in and out and around the tubes, owing 70 to their staggered arrangement, will be more effective than when they are arranged one above the other, permitting the flame to directly ascend between them. It will thus be seen that with a given size of boiler the heating-surface is greatly increased, because there is far less water to the square foot of heating-surface exposed in this construction than when the flames pass through the tubes and the water surrounds them. Besides, a tube 75 may be readily removed when necessary, owing to the man-holes, and another substituted without disturbing the boiler-setting.

Having thus described my invention, what I claim as new, and desire to secure by Letters 85 Patent, is—

1. The combination, in the water-section of a steam-boiler, of the cylinders having convex heads provided with man-holes, the tube-sheet having holes drilled therein in staggered 90 form, the tubes connecting said cylinders having their ends expanded in said holes, and brace-rods extending through the inner surfaces of said tubes and connected to said heads, substantially as described. 95

2. The combination, in a steam-boiler, of the steam-drum, the cylinders having convex outer heads formed with man-holes in their centers, cover-plates for said man-holes, means for securing said plates to said convex heads, 100 the inner tube-sheets having holes arranged in staggered series therein, tubular necks connecting said drum and cylinders, and a series of tubes having their ends expanded in said holes, substantially as described. 105

3. The combination, with a steam-drum having a convex head provided with a man-hole, a removable cover-plate therefor, and means for securing said plate to said head, of a steam-boiler proper consisting of the barrel, the convex heads having man-holes formed in the centers thereof, the removable plates for said man-holes, means for securing said plates to said heads, the tube-sheets forming the inner heads of said barrel and 110 having holes arranged therein in staggered series, the tubes having their ends expanded in said holes and connecting said sheets, the stay-rods having crow-feet extending through a suitable number of said tubes and rigidly 115 secured to the inner sides of said convex heads, and necks connecting said steam drum and boiler, substantially as described. 120

In testimony whereof I affix my signature in presence of two witnesses.
